(57) **CLAIM**

The ornamental design for a power tool, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top, front, and left-side perspective view of a power tool according to a first embodiment of the present invention;

FIG. 2 is a top, back, and left-side perspective view of the power tool shown in FIG. 1;

FIG. 3 is a front elevational view of the power tool shown in FIG. 1;

FIG. 4 is a rear elevational view of the power tool shown in FIG. 1;

FIG. 5 is a left-side elevational view of the power tool shown in FIG. 1;

FIG. 6 is a right-side elevational view of the power tool shown in FIG. 1;

FIG. 7 is a top plan view of the power tool shown in FIG. 1;

FIG. 8 is a bottom plan view of the power tool shown in FIG. 1;

FIG. 9 is a top, front, and left-side perspective view of a power tool according to a second embodiment of the present invention;

FIG. 10 is a top, back, and left-side perspective view of the power tool shown in FIG. 9;

FIG. 11 is a front elevational view of the power tool shown in FIG. 9;

FIG. 12 is a rear elevational view of the power tool shown in FIG. 9;

FIG. 13 is a left-side elevational view of the power tool shown in FIG. 9;

FIG. 14 is a right-side elevational view of the power tool shown in FIG. 9;

FIG. 15 is a top plan view of the power tool shown in FIG. 9;

FIG. 16 is a bottom plan view of the power tool shown in FIG. 9;

FIG. 17 is a top, front, and left-side perspective view of a power tool according to a third embodiment of the present invention;

(Continued)

FIG. 18 is a top, back, and left-side perspective view of the power tool shown in FIG. 17;
 FIG. 19 is a front elevational view of the power tool shown in FIG. 17;
 FIG. 20 is a rear elevational view of the power tool shown in FIG. 17;
 FIG. 21 is a left-side elevational view of the power tool shown in FIG. 17;
 FIG. 22 is a right-side elevational view of the power tool shown in FIG. 17;
 FIG. 23 is a top plan view of the power tool shown in FIG. 17;
 FIG. 24 is a bottom plan view of the power tool shown in FIG. 17;
 FIG. 25 is a top, front, and left-side perspective view of a power tool according to a fourth embodiment of the present invention;
 FIG. 26 is a top, back, and left-side perspective view of the power tool shown in FIG. 25;
 FIG. 27 is a front elevational view of the power tool shown in FIG. 25;
 FIG. 28 is a rear elevational view of the power tool shown in FIG. 25;
 FIG. 29 is a left-side elevational view of the power tool shown in FIG. 25;
 FIG. 30 is a right-side elevational view of the power tool shown in FIG. 25;
 FIG. 31 is a top plan view of the power tool shown in FIG. 25; and,
 FIG. 32 is a bottom plan view of the power tool shown in FIG. 25.
 The surface shading illustrated in the drawings is provided merely to highlight the contour of the design; it is not intended to be illustrative of texture or gloss.
